UNITED STATES PATENT OFFICE.

BURWELL S. CUTLER, OF BUFFALO, NEW YORK, ASSIGNOR TO CUTLER DESK CO., OF BUFFALO, NEW YORK, A CORPORATION OF NEW YORK.

TELEPHONE-STAND.

1,239,890.

Specification of Letters Patent. Patented Sept. 11, 1917.

Application filed May 6, 1916. Serial No. 95,931.

To all whom it may concern:

Be it known that I, BURWELL S. CUTLER, a citizen of the United States, residing at Buffalo, in the county of Erie and State 5 of New York, have invented new and useful Improvements in Telephone-Stands, of which the following is a specification.

This invention relates to a telephone stand and has the object to provide an article for 10 this purpose which is so constructed that it enables a person to be conveniently seated and rest one arm while using the telephone, also to shift the telephone into any desired position as best suits the user, also to provide 15 convenient means for stowing away the telephone directory while the same is not in use and also to provide means which permit of supporting the telephone directory in a convenient position adjacent to the 20 telephone for looking up the name or number as well as enabling a person to make written notations while using the telephone.

In the accompanying drawings:

Figure 1 is a perspective view of a telephone stand showing the preferred embodiment of my invention. Fig. 2 is a fragmentary vertical section, on an enlarged scale, taken through the supporting table, arm and shelf forming part of the telephone 25 stand. Fig. 3 is a similar section taken through the receptacle which is adapted to receive the telephone directory.

Similar characters of reference indicate corresponding parts throughout the several 30 views.

The main frame of this telephone stand is preferably constructed in the form of an ordinary chair upon which the user of the telephone may be seated for the purpose of 35 40 more conveniently carrying on a conversation and also examining the telephone directory or making notes, if desired. This chair may be variously constructed but in the form shown in Fig. 1 the same preferably, 45 though not necessarily, comprises a horizontal seat 1, a plurality of legs 2 supporting the seat, and a back rest 3 projecting upwardly from the rear edge of the seat.

4 represents a table which is arranged above 50 the seat, preferably on the left hand side thereof, and connected at its rear end with the left hand side of the back rest while its front part is supported by a post or stand- 55 ard 5 rising from the seat adjacent to the left front corner thereof. The rear part of

this table is comparatively narrow and forms an arm rest for supporting the left arm of the person while holding the receiver of the telephone to the ear. The front part of this table is comparatively 60 wide so as to serve as a support for a telephone book 22 which is shown by dotted lines in Fig. 1 and may also be used as a support for a pad or a sheet of paper upon which notations may be made. 65

When the telephone directory is not in use the same is preferably stored in an upright position in a rack, receptacle or compartment arranged on the left hand side of the chair between the seat and the table and projecting laterally beyond these members so that the telephone directory may be readily inserted in this compartment and removed therefrom while the telephone user is occupying the seat. In its preferred form 70 75 this directory receptacle comprises lower and upper sections 6, 7, the lower section being constructed in the form of a box which has a closed bottom and which is secured to the lower parts of the back rest and the 80 table supporting post while the upper section is constructed in the form of a rectangular frame which is secured to the upper part of the table post and the adjacent part of the back rest. 85

Above the table are arranged the means whereby the telephone is adjustably supported so that the same may be moved into any desired position as best suits the convenience of the user. Although these supporting means may be varied as to their details of construction the same, as shown in Figs. 1 and 3, are preferably constructed as 90 95 follows:

8 represents a supporting arm which is pivotally secured at its inner end to the upper side of the table adjacent to its outer front corner so as to be capable of swinging in a horizontal plane. The means whereby this pivotal connection between the arm and table is obtained preferably comprises a vertical pivot screw 9 turning in an upright bearing opening 10 in the table and engaging its upper threaded end with the inner end of the supporting arm while its lower 100 headed end bears against the underside of the table by means of an interposed washer 11, as shown in Fig. 2. In order to prevent marring the top of the table by reason of the turning movement of the arm a wearing 105 110

plate or washer 12 is arranged upon the pivot screw 9 between the upper side of the table and the underside of the supporting arm which washer is preferably sunk or let 5 into a recess 13 in the upper side of the table so that the top of the table and the top of the wearing plate are flush. By this means squeaking noise is prevented upon turning the supporting arm in addition to preventing 10 marring of the top of the table, whereby quiet operation of the device is secured and a neat and finished appearance of the same is maintained.

Upon the outer or free end of the supporting arm is mounted a shelf 14 which in turn supports the base 19 of the telephone pedestal. This shelf is preferably mounted on the supporting arm so that it is capable of turning thereon in a horizontal 20 plane in order to permit the telephone to be shifted into the most convenient position. The pivotal connection for this purpose which is shown in Fig. 2, as an example of a variety of ways in which this may be 25 accomplished, comprises a vertical pivot screw 15 which turns in a pivot opening 16 in the outer end of the supporting arm and engaging its upper threaded end in the central part of the shelf while its lower 30 headed end bears against the under side of the supporting arm through the medium of an interposed washer 16. Upon the upper part of this pivot screw between the upper side of the supporting arm and the under- 35 side of the shelf is arranged a metal washer 17 which not only reduces the wear between the relatively movable parts which are preferably made of wood but also prevents any squeaking noise which otherwise would be 40 liable to occur if the shelf were permitted to turn directly on this supporting arm.

On its upper side the shelf which is preferably of circular form is provided with an upwardly projecting marginal guard rim or 45 retaining flange 18 whereby the base of the telephone while resting on this shelf within this rim is prevented from sliding laterally.

In order to permit of securely attaching the base of the telephone to this shelf and preventing the same from becoming accidentally detached therefrom a fastening device is provided which permits of readily attaching the telephone base to or removing the same from this shelf. In its preferred 55 form this fastening device comprises a plurality of spring fingers 20, preferably three in number, as shown in Fig. 1, each of which is secured at its lower end to the outer side

or edge of the shelf by means of a screw 21, as shown, or otherwise, while its upper end 60 is bent so as to project inwardly over the marginal part of the shelf. By this means the telephone base may be readily slipped over the shelf and underneath the inwardly projecting upper ends of the spring fingers 65 so that the latter bear against the upper marginal part of the telephone base and hold the same reliably on the shelf within the marginal guard flange thereof. The telephone as a whole can be also easily removed 70 from this shelf and its retaining fingers if it is desired to use the telephone independently of the telephone stand.

By means of this stand the operation of telephoning may be conducted conveniently 75 and comfortably inasmuch as the person using the same may be seated at this time and rest the arm which holds the receiver on the rear part of this table while the directory or other article is resting on the 80 front part of the table and can be easily manipulated by the other hand. Furthermore, the receptacle which is provided for the telephone directory adjacent to the outer side of the table enables the different telephoning accessories to be kept together as a unit instead of being scattered, thereby 85 greatly facilitating the operation of telephoning. Moreover, this telephone stand as a whole is neat in appearance and does 90 not detract from a room containing other high grade furniture.

I claim as my invention:

A telephone stand comprising a table provided with an inner bearing opening and a recess around said opening, an arm having its inner end arranged over the upper side of that part of the table containing said inner bearing opening and provided at its outer end with an outer bearing opening, an inner pivot screw journaled in said inner bearing opening and engaging its upper threaded end with said arm and its lower headed end with the underside of said table, a plate arranged on said inner pivot screw between said table and arm and engaging with said recess, a shelf arranged above the outer end of said arm, an outer pivot screw journaled in the outer bearing opening of said arm and engaging its upper threaded end with said shelf and its lower headed end with the underside of said arm, and a washer arranged on said outer pivot screw between said arm and shelf.

BURWELL S. CUTLER.
